United States Patent Office

Des. 221,693
Patented Aug. 31, 1971

221,693

CAMERA TRIPOD

Robert W. Bradspies, Pasadena, and Edwin V. Stephens,
Los Alamitos, Calif., assignors to CinTel Corporation,
Los Angeles, Calif.

Filed June 18, 1970, Ser. No. 23,559

Term of patent 14 years

Int. Cl. D16—07

U.S. Cl. D61—1

FIG. 1 is a perspective view of a camera tripod showing our new design; and

FIG. 2 is a side elevational view of the camera tripod;

FIG. 3 is a top plan view of the camera tripod; and
FIG. 4 is a bottom plan view of the camera tripod;
and

FIG. 5 is an enlarged sectional view of FIG. 2 as
taken from lines 5—5.

We claim:

The ornamental design for a camera tripod, substantially as shown and described.
